UNITED STATES PATENT OFFICE

131,037

DESIGN FOR A SHOE HEEL

John Bolten, Andover, Mass., and Robert H.
Goldbaum, Plaistow, N. H.

Application September 19, 1940, Serial No. 95,204

Term of patent 7 years

To all whom it may concern:

Be it known that we, John Bolten and Robert
Goldbaum, citizens of the United States, re-
siding, respectively, at Andover, in the county of
Essex, State of Massachusetts, and at Plaistow, in
the county of Rockingham, State of New Hamp-
shire, have invented a new, original, and ornamental
Design for a Shoe Heel, of which the
following is a specification, reference being had
to the accompanying drawing forming part there-
of, wherein

Fig. 1 is a side elevation of a shoe heel em-
bodying our new design;

Fig. 2 is a front elevation of the same;

Fig. 3 is a top plan view of the same;

Fig. 4 is a perspective view on an enlarged
scale showing the configuration of part of the
surface ornamentation of the heel.

The characteristic features of the invention

comprise a heel of transparent material having
a plurality of symmetrically disposed large spaced
cavities extending downwardly from the heel
seat area, the inner walls of said cavities hav-
ing downwardly diverging grooved surfaces, the
outer walls of the cavities being substantially
parallel to adjacent surfaces of the heel and con-
verging downwardly toward the inner walls, the
surfaces of the outer walls of the respective cav-
ities having a series of downwardly converging
alternately flat and curved ribs and grooves pre-
senting light-reflecting surfaces as shown when
viewed through the exterior of the heel.

We claim:

The ornamental design for a shoe heel, as
shown and described.

JOHN BOLTEN.
ROBERT H. GOLDBAUM.
